UNITED STATES PATENT OFFICE.

WALTER P. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,241,001.

Specification of Letters Patent. Patented Sept. 25, 1917.

Application filed October 9, 1916. Serial No. 124,476.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to outside metal car roofs made of metal sheets which are interlocked at their edges and which are supported upon a suitable substructure.

The invention has to do particularly with the means for securing the roof sheets in place upon the car, and with the means for preventing water from getting beneath the edges of the roof sheets and into the car along the ridge and eaves.

The objects of the invention are to prevent wear on the roof sheets from the fastenings, to avoid straining the sheets from deformations of the car body or the shocks of service, to provide for the easy inspection and for the ready replacement of damaged sheets, and to make a neat appearance.

The invention consists in connecting the sheets by watertight joints, and securing them to the substructure at the ridge so that they cannot move, but holding them down at the ends of the car and at the eaves in such a way that they can move relatively to the substructure. The invention further consists in providing caps for the ends of the car and flashings at the ridge and eaves for holding the edges of the roof sheets and which also assist in keeping water out of the car at these places.

Further objects and details of the invention appear in connection with the following description of the car roof illustrated in the accompanying drawings; and what the invention consists in is further defined in the appended claims.

In the drawings, wherein the same reference characters are used to designate the same parts in the several views,

Figure 1 is a plan view of the end of a car, the running boards and roof sheets being broken away to disclose the ridge and eaves flashings and the roof substructure;

Fig. 2 is a longitudinal section through the end of the car roof, on the line 2-2 in

Fig. 1, looking in the direction of the arrows;

Fig. 3 is a cross-section through the eaves, on the line 3-3 in Fig. 1; and

Fig. 4 is a cross-section through the ridge, on the line 4-4 in Fig. 1.

The car shown in the drawings has a wooden roof substructure comprising a ridge pole 11 and sheathing boards 12 supported upon the side plates 13 and end plates 14 of the car and the suitably spaced car lines 15. The invention is not restricted to any particular kind of car or type of roof substructure, however.

The metal roof consists of sheet metal roof sheets 16 which are arranged in two rows, one on each side of the ridge, the sheets in each row being connected by snugly fitting inverted U-shape side marginal flanges 17 which telescope together to form interlocking standing seams. The ridge ends of the roof sheets have inverted V-shape flanges 18 which nest together one on top of the other, and fit over the middle rib 19 of the ridge flashing strip 20 which is made in one piece or in lapping sections nailed along the ridge from end to end of the car, unlike the construction shown in P. H. Murphy Patent No. 489,822, wherein the ridge T's are separate, one for each pair of roof sheets.

The eaves ends of the roof sheets are turned under, forming flanges 21 which hook under the rebent inner edges 22 of the eaves flashing strips 23. The outer edges of the eaves flashing strips are turned down over the corner of the car and are nailed or otherwise secured to the side of the car. The eaves strips extend from end to end of the car. Corrugations 24 at intervals along the eaves strips stiffen them against bending and lifting up from the car at their inner edges, thereby holding down the eaves ends of the roof sheets.

Corner caps 25 are arranged at the ridge corners of the roof sheets, closely embracing the ends of the side and ridge seams. These corner caps are held in place by bolts 26 which extend through the ridge pole. The bolts 26 also secure the running board saddles 27 to which the running boards 28

are fastened. The ends of the running boards project beyond the ends of the car and are supported by cross pieces 29 and iron braces 30 which are bolted to the ends of the car beneath the roof. 5

The end roof sheets 31 terminate short of the end of the car, and overlap the end flashing strip 32. The inner edge of the end flashing strip is turned up and bent 10 back over the flashing strip to form a lip 33 upon which the edges of the end roof sheets rest. This lip 33 also keeps water from running under the edges of the end roof sheets and thus into the car. End caps 34 at each end of the car cover the end flashing strips 32 and edges of the end roof sheets. The end caps and end flashing strips are turned down over the ends of the car and nailed in place. The end caps have trans- 15 verse corrugations 35 for stiffening them and preventing their inner edges from lifting up. 20

This arrangement of the side and end eaves flashings and fastenings permits the roof sheets to move upon the substructure at all 25 points except along the ridge, and thus distortions of the car which result in movements of the ends and sides of the car with respect to the ridge have no harmful effect 30 upon the roof sheets. The roof sheets are held in proper alinement upon the substructure by the ridge corner caps and by their engagement with the ridge flashing strips, whereby all other positioning means may be 35 dispensed with, and wear and strains upon the roof sheets due to contact with fastenings along the eaves are eliminated.

It is evident that changes, may be made 40 in the form and proportions of the roof sheets, flashing strips and caps without affecting their functions, and the invention is not restricted to the particular details of construction shown in the drawings.

I claim the following as my invention:

45 1. A metal car roof comprising roof sheets arranged in rows on each side of the ridge, said roof sheets having flanges along their side and ridge edges which are connected to form seams, said roof sheets being fixedly secured to the roof substructure along the ridge so as to maintain an unbroken line at their ridge ends and freely movable upon the roof substructure along the eaves and at the ends of the car, whereby an alinement of the ridge ends of the roof sheets is maintained notwithstanding the distortion of the sides and ends of the car. 50

60 2. A metal car roof comprising roof sheets arranged crosswise of the car, said roof sheets having flanges along their side edges which are connected by a telescoped and interlocked joint to form seams, said roof sheets being fixedly secured to the roof substructure along the ridge so as to maintain 65 an unbroken line at their ridge ends and

freely movable upon the roof substructure along the eaves and at the ends of the car, whereby alinement of the ridge ends of the roof sheets is maintained notwithstanding the distortion of the sides and ends of the car. 70

3. A metal car roof comprising roof sheets arranged crosswise of the car, said roof sheets lapping along their side edges, which are secured together to form seams, said roof sheets being fixedly secured to the roof substructure along the ridge so as to maintain an unbroken line at their ridge ends and freely movable upon the roof substructure along the eaves and at the ends of the car, and means engaging the under sides of 75 said sheets at their ends for loosely holding them down, whereby the alinement of the roof sheets at their ridge ends and continuity of the roof is maintained notwithstanding the distortion of the sides and ends of the car. 80

4. A metal car roof comprising roof sheets arranged crosswise of the car, said roof sheets lapping along their side edges, which are secured together to form seams, said roof sheets being fixedly secured to the roof substructure along the ridge so as to maintain an unbroken line at their ridge ends and freely movable upon the roof substructure along the eaves and at the ends of the car, rebent means engaging the under sides of 90 said roof sheets for holding down their eaves ends, and end caps secured to the ends of the car and lapping over the edges of the end roof sheets inwardly from the ends of the car, whereby the alinement of the ridge ends of the roof sheets and continuity of the roof is maintained notwithstanding the distortion of the sides and ends of the car. 95

5. A metal roof comprising an end roof sheet having its outside edge raised and freely movable upon the car at one end, an end flashing strip arranged beneath said raised edge of said sheet, and an end cap secured to the end of the car and projecting over on top of the edge of the roof sheet to hold it down upon the flashing strip. 100

6. A metal roof comprising end roof sheets 115 freely movable upon the car at its ends, end flashing strips having upturned flanges along their inner edges arranged beneath the edges of the roof sheets with a space intervening between the upper side of the 120 flashing strips and lower side of the edges of the roof sheets, and end caps secured to the ends of the car and spaced above the flashing strips and lapping over on top of the edges of the roof sheets to hold them 125 down upon the flashing strips.

7. A metal car roof comprising roof sheets arranged side by side, said roof sheets lapping along their side edges to form seams, 130 said roof sheets being fixedly secured to the

roof substructure along the ridge so as to maintain an unbroken line at their ridge ends and freely movable upon the roof substructure along the eaves and at the ends of the car, the ends and edges of said roof sheets terminating on top of the car, end caps secured to the ends of the car and lapsing the end roof sheets, and means protecting the eaves and engaging the eaves

ends of said roof sheets to hold them from 10 lifting up, whereby the alinement of the roof sheets and their continuity at the seams are maintained notwithstanding the distortion of the sides and ends of the car.

Signed at St. Louis, Missouri, this fifth 15 day of October, 1916.

WALTER P. MURPHY.
